DESIGN FOR A REFRIGERATING CASE FOR BOTTLED BEVERAGES

Elmer C. Johnson and Jerome E. Hagstrom, Kansas City, Mo., assignors, by mesne assignments, to The Vendo Company, Kansas City, Mo., a corporation of Missouri

Application October 25, 1948, Serial No. 149,278

Term of patent 14 years

(Cl. D67—3)

To all whom it may concern:

Be it known that we, Elmer C. Johnson and Jerome E. Hagstrom, both citizens of the United States, residing at Kansas City, in the county of Jackson and State of Missouri, have invented a new, original, and ornamental Design for a Refrigerating Case for Bottled Beverages, of which the following is a specification, reference being had to the accompanying drawing forming a part thereof.

Figure 1 is a perspective view of a refrigerating case for bottled beverages, showing our new design; and

Fig. 2 is a side elevational view thereof.

The back of the case not shown is substantially plain.

We claim:

The ornamental design for a refrigerating case for bottled beverages, as shown and described.
